UNITED STATES PATENT OFFICE.

WILLIAM T. ROLPH AND HUGO R. KUERSTEN, OF CHICAGO, ILLINOIS; SAID KUERSTEN ASSIGNOR TO SAID ROLPH.

TUFT-CLEANING BRUSH.

SPECIFICATION forming part of Letters Patent No. 738,487, dated September 8, 1903.

Application filed September 16, 1902. Serial No. 123,579. (No model.)

To all whom it may concern:

Be it known that we, WILLIAM T. ROLPH and HUGO R. KUERSTEN, residing at Chicago, in the county of Cook, State of Illinois, have 5 invented certain new and useful Improvements in Tuft-Cleaning Brushes, of which the following is a specification.

This invention relates to improvements in brushes designed particularly for use in cleaning the tufts of upholstered furniture and carriage backs or cushions.

The invention consists generally in a brush having a central stud adapted to rest upon the button forming the tuft of the article, 15 with means for rotating said brush while the stud bears upon said button.

The invention consists, further, in the constructions and combinations hereinafter described, and particularly pointed out in the 20 claims.

In the accompanying drawings, forming part of this specification, Figure 1 is a partial vertical section of a brush embodying our invention. Fig. 2 is a side elevation showing 25 a modified construction. Fig. 3 is a detailed section of the construction shown in Fig. 2.

In the drawings, 2 represents the brush-head, and 3 the bristles or fibers thereof. The head is provided with the central stud 4, preferably provided with the block 5 at its lower 30 end, said block being concaved at the bottom to permit it to rest firmly upon one of the buttons 6 of the article to be cleaned.

Any suitable means may be used for rotating 35 the brush, but we prefer to use a spirally-grooved shaft 7, secured to the brush-head 2 and having its upper end arranged within a handle 8. A spiral spring 9 is arranged within the handle and bears upon the upper end 40 of the shaft 7, and this spring tends to hold the handle in an elevated position. At the lower end of the handle a sleeve 10 is provided, secured in position by means of suitable screws 11, and the shaft 7 is provided 45 with an enlarged head 12 above this sleeve, upon which the spring 9 rests. Suitable lugs 13, within the sleeve 10, engage the spiral

groove in the shaft 7, so that as said sleeve 10 travels along the shaft said shaft is caused to rotate, and as the sleeve is reciprocated 50 the shaft is rotated first in one direction and then in the other.

In using the device the block 5 is placed upon the top of one of the buttons within a tuft of the furniture. Pressure is then applied to the handle 8, and as this handle slides down over the shaft 7 against the tension of the spring 9 said shaft is rapidly revolved in one direction and the brush is revolved with it. When the sleeve has traveled down to the lower part of the shaft 7, 60 pressure is relieved and the spring 9 forces the handle 8 to raise, and thereby reverses the rotation of the shaft 7, causing the brush to rotate in the opposite direction. By moving the handle up and down a rapid rotation may be given to the brush, and thereby the 65 depression or tuft of the furniture may be rapidly cleaned, which could not be done with any ordinary brush.

In Fig. 2 we have shown a longer shaft 7 than that represented in Fig. 1 with a handle 14, adapted to be moved up and down on a shaft and provided with suitable studs or ribs 13', 70 engaging the spiral groove in the shaft for 75 the purpose of rotating said shaft and brush.

We do not limit ourselves to the details of the construction herein shown and described, as the same may obviously be varied without departing from our invention.

We claim as our invention—

1. The combination, with a brush having a central stud adapted to rest upon a tufting-button, of a spirally-grooved shaft to which said brush is secured, and a sliding handle 85 engaging said shaft and adapted to rotate said shaft and brush as it is reciprocated on said shaft.

2. The combination, with a suitable brush-head, of a central stud adapted to rest upon a tufting-button and forming a pivotal support for said brush, and means for rotating said brush, substantially as described.

3. The combination, with a suitable brush

provided with a central stud adapted to rest upon a tufting-button, of a spirally-grooved shaft to which said brush is secured, a reciprocating handle 8 engaging said spiral shaft, and a spring arranged within said handle and bearing upon the end of said shaft, substantially as described.

In witness whereof we have hereunto set our hands this 8th day of September, 1902.

WILLIAM T. ROLPH.
HUGO R. KUERSTEN.
